UNITED STATES PATENT OFFICE.

HENRY JEFFREY, OF AURORA, INDIANA.

RAILWAY-CROSSING.

SPECIFICATION forming part of Letters Patent No. 240,519, dated April 26, 1881.

Application filed January 22, 1881. (No model.)

To all whom it may concern:

Be it known that I, HENRY JEFFREY, of Aurora, State of Indiana, have invented a new and useful Improvement in Railway-Crossings, which improvement is fully set forth in the following specification and accompanying drawing, in which the figure is an isometric view of the crossing.

The present invention is an improvement on crossings for which Letters Patent were issued to me August 19, 1879, and numbered 218,632. As stated in said patent, the corners of the crossing were formed of independent and separable pieces joined at their middles and having their ends serve as splice-plates with the track-rails.

The object of this invention is to provide a crossing with solid corners, and having the ends of this solid cross so constructed that they will serve as splice-plates for the track-rails, as will be hereinafter more fully set forth.

In the accompanying drawing, A represents the cross, cast or forged in one piece, so that the limbs of the cross project at any angle suitable for the tracks.

Along the inner edges of the limbs, at the point of unity, grooves B are formed for the flange of the wheel, as stated in the patent referred to.

Along the inner side of the limbs, near the ends, they are halved or cut away, C, so that when the ball of the rail is placed therein the inner surface will be flush with the inner surface of the limb. In practice, I prefer to have the solid crossing cast as thick as the height of the T-rail and the lower corner rabbeted, as shown at D, to permit the lower flange of the rail to rest therein. If desired, however, the

cross may be cast thicker than the height of the rail without departing from the spirit of my invention.

E represents the end of the track-rail, and E' the short pieces necessary to fill up the space between the tracks.

It will be observed that the inner limbs, F F, are made just half the length of the distance between the rails, so that by placing in position four crossings the limbs F of the four crossings will meet each other.

The rails are suitably bolted to the limbs of the crossing, as shown, and thereby form a solid and serviceable crossing, not liable to break, and when injured can readily be replaced by a duplicate cross.

I am aware that a solid crossing, or a crossing formed of one piece of metal, cast or forged, is not new. My invention does not consist in this, but in adapting this solid cross or crossing so that the ends of the T-rails will lap over on the limbs of the said solid cross.

Having described my invention, what I claim as new, and desire to secure by Letters Patent, is—

A crossing-frog composed of one piece of metal, cast or forged in the form of a cross, having the parts of its members at their intersection formed to serve as track-rails, and their ends serving as splice-plates with the track-rails, in combination with the track-rails, substantially as herein set forth.

HENRY JEFFREY.
